UNITED STATES PATENT OFFICE.

EWALD VON SYO, OF AUGSBURG, GERMANY, ASSIGNOR TO PHILIPP ADAM TAFEL.

MAGNETIC SEPARATOR FOR GRAIN.

SPECIFICATION forming part of Letters Patent No. 440,070, dated November 4, 1890.

Application filed May 14, 1890. Serial No. 351,791. (No model.)

To all whom it may concern:

Be it known that I, EWALD VON SYO, a subject of the German Emperor and a resident of Augsburg, in the Kingdom of Bavaria, Germany, have invented certain new and useful Improvements in and Relating to Separation of Iron and other Magnetic Impurities from Grain and other Materials, of which the following is a specification.

10 My invention relates to a novel method of and apparatus for separating magnetic impurities, which are frequently found in grain or other granular or pulverized materials; and the object of my said invention is to provide 15 a rotating drum with a number of annularly-arranged magnets over the free poles or sides of which the material to be separated is conducted by means of an inclined channel in such a manner that the magnetic impurities 20 or particles become attracted by the rotating magnets and carried outside the said channel, where they are scraped off and separately collected. I obtain these objects by the arrangements illustrated in the accompanying drawings, in which—

Figure 1 is a vertical section of an apparatus constructed according to my said invention; Fig. 2, a top view of the supply-channel and the rotating drum with the magnet-nets, of which Fig. 3 represents a modification.

The magnets *f*, which may be either permanent or electro magnets, are arranged within the rotating drum *b*, so as to have their free poles or sides within the upper face of the drum in the form of one or more rings, Figs. 2 and 3. The rotating drum *b*, which may be actuated from the driving-pulley *k* on the shaft *i*, through the medium of the bevel-gears *l m*, 35 is situated within a corresponding circular aperture of the bottom *a* of an inclined channel *A* in such a manner that the face of the rotating drum, the actual poles or sides of the magnets *f*, and the bottom *a* of the conducting-channel *A* will form a continuous inclined plane, Fig. 1. In the direction of rotation 40 of the said magnet-drum *b*, each side wall *c d* of the conducting-channel, which is so situated and of such a width in relation to the 45 annular magnetic field that the outlines of the channel form secants of the inner circle

of the magnet-ring, is provided with a port or ports *g* and *h* for the passage of the magnetic impurities or particles attracted by the magnets *f*. In consequence of the rotation 55 of the latter, the magnetic impurities or particles are conducted outside of the inclined channel and scraped off from the magnets as soon as they meet the solid outer face of the corresponding side walls *c d* of the channel, 60 where they may be conveniently discharged. In this manner the material to be purified or separated is caused to pass over two magnetic fields for the purpose of securing a thorough purification or separation of the said 65 material from the magnetic parts. The said conducting-channel *A* and magnet-drum *b* is arranged inclined to the horizontal in such a degree as to provide the necessary slope for the material to be transported over the magnetic fields by its gravity.

In several cases for separating magnetic ores from their gangue, I may arrange two or more rotating magnetic drums *b* in the same channel, or I may arrange the series of magnets side by side, in order to obtain a thorough separation of the magnetic particles, as seen in Fig. 3.

In order to separate the magnetic impurities or particles from diamagnetic parts adhering thereto, I may provide bristles or brushes *g'* made of other material within the ports *g* and *h* of the side walls of the conducting-channel *A*, which are adapted to retain such diamagnetic parts within the channel, 80 such brushes being shown in Figs. 1 and 2.

Having now fully described my invention, what I claim, and desire to secure by Letters Patent, is—

1. The apparatus for separating magnetic particles or impurities from grain or other granular or pulverized materials, consisting of the combination of one or more rotating inclined drums in the face of which the free poles or sides of permanent or electro magnets are arranged in the form of a ring or 90 rings, and an inclined channel arranged to receive within apertures of its bottom the said magnet-drum or drums in such a manner that the face of the rotating magnet drum or 95 drums, the free poles or actual sides of the magnets, and the bottom of the conducting- 100

channel will form a continuous inclined plane, substantially as and for the purpose set forth.

2. As an improvement in apparatus for separating magnetic particles or impurities from grain or other granular or pulverized materials, the combination, with one or more rotating drums having within their face permanent or electro magnets annularly arranged, of an inclined channel, being adapted to receive said drum or drums within corresponding apertures of its bottom and having in its side walls suitable ports for the pas-

sage of the magnetic particles attracted by the magnets, substantially as and for the purpose hereinbefore described.

In testimony that I claim the foregoing as my invention I have signed my name, in presence of two witnesses, this 25th day of April, 1890.

EWALD VON SYO.

Witnesses:

PAUL VOGEL,
M. SUNTHEIMER.
